TOY ELECTRIC TRAIN APPARATUS

Harry C. Stearns, Oak Park, Ill.

Application July 28, 1932, Serial No. 625,374

13 Claims. (Cl. 104—149)

The present invention relates to toy electric train apparatus.

The general object of the invention is to provide an improved automatic controller device, improved track equipment and improved electric locomotives which will enable the electric trains and the appurtenant track devices to simulate practically all typical railroad conditions and operations, including the stopping and starting of the trains at depots, switches and semaphores, the operation of semaphore lights and signals and road crossing lights and signals, the throwing of track switches in timed relation to the movements of different trains, as for causing one train to take a siding or spur track while passing another train on the main track, etc., the reversing of the trains, the operation of the trains at different speeds, and numerous other operations hereinafter described.

With regard to the controller device, it is an object of the invention to provide an improved controller device which will automatically perform the various circuit controlling operations for controlling the transmission of current to the trains, track switches, semaphores, lights, etc. One of the features of this controller device is that it enables any circuit controlling operations to be very accurately timed, both with respect to the length of time the circuit is opened or closed as well as the instant of time any control operation starts or stops in its relation to some other control operation. This accuracy of timing enables any single-train cycle to faithfully simulate actual train conditions in the close synchronization between the movement of the train and the throwing of track switches, operation of semaphore signals, etc.; and this accuracy of timing is of decided importance in multiple-train operation where very close synchronization is frequently required between the operation of two or more trains and associated track equipment in order to avoid collisions and accidents. Another feature of this controller device is that it is extremely flexible, changeable and adaptable, in order to facilitate the establishment of any desired cycle of operations on the controller device, and to permit this cycle to be quickly and easily modified for any later conditions or desired changes. This feature is of educational benefit and assists greatly in maintaining interest by inducing the child to work out different cycles or sequences of operation, particularly when using two or more trains in the cycle. In its preferred embodiment, this controller device utilizes a traveling tape 55 composed of paper or the like in which perfora-

tions are cut for establishing circuit connections at predetermined time intervals and in predetermined sequence. In this construction, close accuracy of timing can be obtained by minute variations in the length or position of the perforations, and flexibility for establishing a new or modified cycle is afforded by the fact that the perforations can be changed or varied, or a new paper tape substituted.

Another object of the invention is to provide an improved control apparatus having the dual feature of enabling the child to perform part of a typical cycle of operations automatically and to perform another part of the cycle manually, or to perform all of the control operations manually. For window display purposes, the completely automatic operation would generally be preferable, but for home use there might be occasions when the child would prefer to perform some of the controlling operations himself. The present apparatus is adaptable to both requirements in enabling different control operations to be performed either automatically or manually; in one preferred embodiment including a manually operated keyboard in conjunction with the perforated paper tape. My improved control apparatus, in addition to controlling the time and duration of circuit closing and opening operations can also effect voltage changes, reversals of polarity, etc., also in timed relation, for numerous other control functions which will be later described.

With reference to the track equipment, one of the objects of the invention is to provide an improved control track section having a particular relation of two selectively energized third rail sections, arranged for causing selective actuation of a reversing switch in the locomotive. The two insulated third rail sections are wired to the above mentioned control device whereby the selective energization of these third rail sections is automatically controlled thereby, the operating relation being such that the train may be caused to pull in on a siding and to have a reversing switch in the locomotive selectively energized either for causing the train to back out of the siding or to continue ahead on or out of the siding when the locomotive is later energized. This is merely exemplary of but one of the control operations which it is possible to obtain with my improved control track section.

Another object of the invention is to provide an improved track switch embodying automatic means which operates to place the shiftable switching rail under the control of a train ap-

proaching and passing over said track switch, whereby the switching rail is automatically held in its previously shifted position. This improved track switch positively avoids one of the objectionable characteristics of prior track switches, namely, the tendency of the shiftable switching rail to be shifted to a neutral or different position by the vibration of a passing train, with the consequent derailment of a portion of the train.

With reference to the locomotives, one of the objects of the invention is to provide an improved electric locomotive characterized by automatic control apparatus in the locomotive, responsive to a change of voltage received from the track, for causing the locomotive to change its direction of travel, or to cause it to change its speed of travel, or both. Another object is to provide an electric locomotive characterized by an improved motor which is more efficient, delivers more constant torque, and operates at a substantially constant selected speed under varying operating conditions. This improved motor also avoids all brush and commutator trouble which has been so prevalent in prior toy locomotives.

Other objects, features and advantages of the invention will appear from the following description of certain preferred embodiments of the invention. In the accompanying drawings illustrating such embodiments:

Figure 1 is a diagrammatic view illustrating one of the innumerable track layouts which may be devised in connection with the present invention, this layout being chosen to represent a fairly wide variety of typical railroad conditions and operations;

Figure 22 is a detail section showing the connector couplings used with the conductor illustrated in Figure 21.

The track layout illustrated in Figure 1 comprises any preferred grouping of straight and 35 curved lengths of track T1, T2, T3, etc., arranged to form loops, sidings, intersections, crossovers, etc., in any desired relation. The track switches are indicated generally at S1, S2, S3, etc. The track structure in general is of the conventional third rail toy design having the two outer rails r1 and r2 grounded to metallic cross ties and having a central third rail r3 which is suitably insulated from the other rails and from the cross ties. Interposed at various points in the track 45 layout are control track sections CS1 and CS2 in which one or more sections of third rail r3 are electrically insulated from the third rails of adjoining track sections. The toy locomotives are indicated at L1, L2, the cars drawn by these 50 locomotives being omitted for simplicity of illustration.

Any number of typical accessory devices may be associated with the track layout, such as the semaphore signals 24, the crossing gate 25 at 55 one road crossing, the blinker signal lights 26 and the ringing signal lights 27 at other crossings, the depot 28, power plant 29, etc.

Referring now to the controller device, designated C, which is adapted to control the transmission of current out over the various circuit connections to the different parts of the system, attention is first directed to Figures 2 to 6, inclusive, illustrating the preferred form of such controller unit. It comprises a drum 32 which is 65 rotatably supported on a base plate 33. Rising from one end of this base plate is a supporting frame or standard 34 which supports the driving spindle or shaft 35 on which one end of the drum is mounted, and rising from the other end of the 70 said base plate is a standard 36 carrying a releasable spindle or tail stock 37 on which the other end of the drum is rotatably supported. The drum is adapted to be rotated at a very slow speed, and this may be effected by hand rotation, 75

by a clock spring type of motor or by an electric motor. Preferably an electric motor, indicated at 41, is employed, such motor being shown as secured to the end frame structure 34 and having its armature operatively connected with the driving shaft 35 through a speed reduction gear train enclosed within a housing 42. In situations where one revolution of the drum 32 is to effect one complete cycle of operations or events, I have found that the drum may be rotated as slow as one revolution every five or six minutes or even slower, so that a wide variety of operations can be brought about within this one cycle of drum movement. It is desirable for the proper synchronizing of the movements of different trains, particularly in situations where one train has pulled up on a siding to permit the passing of another, or where one train is waiting at a crossing for another, that the speed of rotation of the drum 32 be substantially constant and independent of voltage changes. Because of this desideratum I preferably employ, in alternating current systems, a self-starting synchronous motor which will always rotate at the fixed speed determined by the current alternations, independently of voltage change and independently of any torque changes arising in such a device. Figure 3 illustrates the motor 41 as being of a self-starting synchronous type such as is used in electric clocks. The use of such a motor enables the desired precision movement of the drum 32 to be obtained, although it will be understood that an induction motor, commutator motor or other type of motor may be employed, particularly in installations where timing sequences are not very close and where there are no voltage changes on the supply circuit. In this regard, I also contemplate employing self-starting synchronous motors in the toy locomotives L1, L2, which motors will maintain a substantially constant selected speed independently of voltage change, thereby cooperating with the synchronous motor drive of the drum 32 for obtaining precision relationship between the movement of the drum and the extent of travel of the trains.

Referring to Figure 5, the rotative movement of the shaft 35 is transmitted to the drum through a ratchet wheel 44. A spring pressed pawl 45, pivotally mounted on the end of the drum, engages in the teeth of the ratchet wheel, which face in a direction for transmitting positive advancing movement to the drum. Such arrangement permits the drum to be advanced freely by hand in its forward driven direction, which is of advantage when a set-up of operating conditions is first being established in the cycle of the controller device. The end of the shaft 35, beyond the ratchet wheel 44, is adapted to engage in a bearing socket 46 in the head of the drum, enabling the drum to be separated from the shaft for facility in mounting the paper tape thereon, or for any other purpose. The opposite spindle 37 likewise has its inner end mounted in a bearing socket 47 in this end of the drum, and said spindle is arranged for movement endwise in the standard 36 whereby the spindle can be withdrawn from the socket to permit removal of the drum.

In the preferred construction, the drum, as previously remarked, has a thin sheet of insulating material 51 wound about the same, composed of paper, fabric, celluloid or the like, and the circuit controlling functions are provided for by cutting slots or holes in this insulating sheet through which contact fingers *f* can make contact with a metallic surface below the sheet.

Figure 2 illustrates one preferred manner of constructing a drum adapted to use this insulating sheet. A cylindrical tube 52 constitutes the body of the drum, being joined to end heads 53 and 54 in which the bearing sockets 46 and 47 are provided. One or both end heads are releasably secured to said tube, the end head 54 being shown as provided with holes for receiving screws 55 which thread into tapped sockets 56 formed in the end of the sleeve 52. Preparatory to securing said removable end head to the tube, there is first assembled over the tube an insulating sleeve 58 of fibre or the like, insulating end washers 59, and a plurality of metallic sleeves, there being four of these sleeves shown, designated 61, 62, 63 and 64. Insulating spacing rings 65 are interposed between the adjacent ends of the four metallic sleeves, these spacing rings being of approximately the same outer diameter as the sleeves for presenting a smooth outer cylindrical surface for the insulating sheet 51. The outer ends of the two end sleeves have radially projecting flanges 61' and 64' which form marginal shoulders defining the position of the sheet 51 on the drum, these flanges also serving as contact rings against which suitable brushes bear for completing circuits through the sleeves 61 and 64. The tightening of the end head 54 clamps the four conducting sleeves and the cooperating insulating elements to the drum so that they all rotate together.

The contact fingers *f* which bear against the surface of the drum are arranged in a bank along one side of the drum, and preferably consist of lengths of spring wire having their upper curved ends bearing resiliently against the insulating sheet 51 and having their lower portions anchored in a longitudinally extending terminal bar 71. These spring contacts are divided into groups for completing circuits through the conducting sleeves 61, 62, 63 and 64, respectively. Whenever a solid part of the insulating sheet 51 is interposed between a particular contact finger and its respective conducting sleeve the circuit is open through said contact finger, and whenever a slot or hole 51' in the insulating sheet moves into register with the end of the finger the latter is enabled to contact with its respective sleeve, thereby completing a circuit through that finger. To facilitate the operation of cutting the appropriate slots and holes in the sheet for obtaining the different timed relations in the operating cycle, the sheet may, if desired, be provided with circumferential and crosswise markings, the circumferential markings representing the different contact fingers and the crosswise markings representing intervals of time or motion in the rotation of the drum.

Figure 4 illustrates one preferred method of securing the insulating sheet to the drum. Each of the conducting sleeves 61-64 is formed with an outwardly spaced fin or flange 76 extending lengthwise of the sleeve and spaced slightly from the peripheral surface of the drum to form a small lip or pocket 77 extending along the length of the sleeve. One edge of the insulating sheet is folded backwardly, as indicated at 78, and this folded edge is hooked over the edge of the flange 76, into the lengthwise pocket 77. The sheet is then wrapped around the drum and its free edge is tucked into the pocket 77 between the folded edge of the sheet and the cylindrical surface of the drum. Each of the four conducting sleeves 61-64 is constructed with a similar lip or flange 76 and pocket 77, all longitudinally

aligned, whereby the same strip of paper or other insulating material can be used to cover all four conducting sleeves. The paper sheet or tape is wrapped around the drum in a direction such that the rubbing friction of the contact fingers *f* tends constantly to wrap the sheet tighter by forcing its free edge into the pocket *71*, such avoiding the necessity of any fastening means and also assuring a smooth surface. The sheet or tape *51* may consist of paper, celluloid, or a fabric such as glazed linen or the like, or any other material which can be easily perforated and which will still have the requisite stiffness to prevent wrinkling after it has been wrapped around the drum. As an alternative arrangement, the drum may be coated with a film of varnish, lacquer, enamel or the like, and the perforations *51'* can be made or altered by scratching through this film.

20 Figure 2 illustrates diagrammatically some of the circuit connections for conducting different polarities and different potentials to the conducting sleeves *61*—*64*. The apparatus is operable either on direct current or on alternating current, but since most constructions employ alternating current the apparatus will be described in that relation. A typical toy train transformer is indicated at *82*, comprising a primary winding *63* and a multiple-tap secondary winding *84*, the 25 multiple taps of this secondary winding affording different voltages. Where the electric motor *41* for driving the drum is of the synchronous-speed clock type, this motor will usually be connected across the primary leads of the transformer so as to operate on the full 110 volts. For the purposes of illustration, I have shown the conducting sleeve *61* as controlling "ground" 30 circuits, such being the circuits connecting with the two outside ground rails *r1* and *r2* of the track sections, which "ground" circuits may also include switches, lights and other appurtenances which are responsive to this "ground" polarity. I have shown the conducting sleeve *64* as serving to control "third rail" circuits, which circuits 35 connect with the third rails *r3* of the track sections and also with any switches, lights, etc. which may be responsive to this "third rail" polarity. Some manufacturers of toy train equipment construct their switches, semaphore lights, etc. so as to be responsive to "ground" polarity and others manufacture these same accessories so as to be responsive to "third rail" polarity. In order to make the present controller apparatus 40 universally adaptable to all types of accessories, I have shown the drum as being provided with the "ground" conducting sleeve *61* and the "third rail" conducting sleeve *64* but it will be understood that should the device be manufactured solely for one type of equipment, one of these 45 sleeves might be omitted.

The two intermediate conducting sleeves *62* and *63* are provided for obtaining different voltages, such being of advantage for automatically reversing the trains, changing their speed of 50 operation and performing other control operations as will hereinafter appear. I have shown two sleeves *62* and *63* for obtaining two voltage changes, separate from the normal voltage, but it will be understood that any desired number of 55 these voltage change sleeves may be employed. The lengths of the separate conducting sleeves *61*, *62*, *63* and *64* may be proportioned in any desired relation for accommodating different numbers of contact fingers *f*.

75 At any instantaneous voltage condition, a wire

86 conducts one polarity to "ground" sleeve *61*, a wire *87* conducts the other polarity to "third rail" sleeve *64*, and two other wires *88* and *89* conduct different voltages to the two intermediate sleeves *62* and *63*. The wire *86* connects with connector terminal *86a* which is attached to a bus strip *86b*, and extending from the latter is a main contact finger *86c* which bears against the protruding flange *61'* of the sleeve *61* for conducting this polarity to that sleeve. Likewise, the wire *87* connects to terminal *87a* attached to bus strip *87b*, from which contact finger *87c* extends and bears against the flange *64'* of sleeve *64*. The other two wires *88* and *89* have similar connections with terminals *88a* and *89a* attached to bus strips *88b* and *89b* having main contact fingers *88c* and *89c* extending therefrom. The two latter contact fingers *88c* and *89c* may have continuous contact with their respective sleeves *62* and *63* through continuous circumferential slots 20 cut in the sheet *51*, or they may have intermittent contact with their respective sleeves through spaced slots cut in the sheet. If desired, the two wires *88* and *89* might establish connection with their respective conducting sleeves through an internal arrangement of slip rings and contact brushes disposed on the inner side of the control drum, or arranged on one end head of the drum. The four bus strips *86b*, *87b*, *88b* and *89b* are all mounted in insulated relation on an insulating strip *91*.

The individual contact fingers *f* controlling the individual circuits are all mounted on the aforementioned horizontal insulating bar *71* which is supported at its ends on standards *93* rising from the base plate *33*. As shown in Figures 3 and 4, said terminal bar *71* may be composed of outer and inner sections *71a* and *71b*, and the contact fingers *f* are preferably in the form of short lengths of spring wire clamped between the bar sections. Each contact spring has a bent or curved upper end *f5* bearing against the drum, and is formed intermediate its ends with a looped portion *f6* which is extended through an aperture in the outer bar section *71a* up to the surface of the bar. Here this looped portion has electrical connection with a suitable connector terminal *98*, such being shown in the form of a screw passing through a terminal clip and thence through the outer looped portion *f6* of the contact spring and threading into the insulating bar section *71a*. These connector terminal screws *98* are arranged in two rows across the length of the terminal bar *71*, being staggered or offset for more compactly disposing these terminals and their respective contact springs. A trough or channel *101* may be provided along the lower edge of the outer bar section *71a*, in which may be laid the various wires leading to the different connector terminals *98*.

Where a manually operated keyboard is desired in the controller device *C*, each contact spring *f* continues down from the terminal bar *71* and curves forwardly to provide a contact end *f8* on which a key head or button *f9* is secured. The buttons on successive contact springs are arranged in two staggered rows (Figure 3) for more compact grouping of these buttons. It will be observed from Figures 3 and 6 that these key extremities *f8* are disposed directly above the bus strips *86b*, *87b*, etc., corresponding to the respective conducting sleeves *61*—*64*. That is to say, by depressing the key extremity *f8* of any one of the contact springs *f* associated with the con- 75

ducting sleeve 61, a circuit is established from the bus strip 86b directly to the key end of the contact spring, whereby a shunt is established across the contact sleeve 61 and contact finger f, so that a current flow is established through the circuit wire connecting to that particular contact finger, independently of whether or not there is a slot in the paper tape 51 directly under the upper end f5 of that contact spring at that time. 5

10 By providing this relation of manually operated key extensions f8 on each of the contact fingers f, the present control device is made capable of use in a dual capacity, either for the automatic despatching and controlling of trains and associated apparatus, or for the manual despatching and control thereof. For an entirely manual control, the circuit of the motor 41 is interrupted for stopping the motion of the drum 32, and thereupon all of the circuits associated with the four 15

20 conducting sleeves 61—64 may be manually controlled by selectively or simultaneously depressing different buttons f9 of this manual control keyboard, which I have designated in its entirety as K. Said manual control keyboard may also be operated to add interest and instruction during the automatic operation of the system, while the drum 32 is rotating, at which time it enables one to manually interpolate or vary certain control functions in the automatic cycle of events. The 25

30 manual control keyboard may also be used in predetermining timing relations and time intervals while setting up or modifying an automatic cycle in the paper tape 51; for example by depressing the appropriate key one train may be advanced, or a track switch thrown or other operation performed, and the necessary length and position of the slot in the paper tape noted for performing this circuit closing operation in its proper relation in the automatic cycle. While 35

40 this manual control keyboard K is an advantageous part of the controller device C, particularly when it is desired to be able to perform numerous control operations manually, nevertheless it will be understood that said keyboard can 45 be omitted from the controller if desired.

The present form of controller using the insulating tape 51 of paper or the like enables the timed relations to be very accurately determined. The length of the slots 51' can be calculated 50 down to very fine dimensions (in the neighborhood of 1/64 of an inch or even less). If a slot should be cut too long it is a simple matter to paste a small tab of paper across the end of the slot. Variations in the cycle can be easily made 55 by differently cutting, changing or closing the slots, or by substituting a new sheet 51.

Figure 7 illustrates a modified construction which enables a plurality of voltage changes to be obtained from only a single conducting sleeve. 60 In this arrangement a series of contact springs f12, f13 and f14 are mounted on the terminal bar 71 in superposed relation, whereby they all track on the same peripheral portion of the drum, but contact with the sheet 51 at angularly spaced 65 points along this path. The other extremities of the free contact springs are connected together by resistances f12 and f13. This arrangement may be employed to vary the potential which is given to the conducting sleeve associated with said 70 contacts, such being the preferred adaptation; or, if a constant potential is always transmitted to said sleeve through other contact means, this arrangement of contacts f12, f13 and f14 may be employed to vary the potential which is transmitted from said sleeve out through these contacts 75

to the particular piece of apparatus then being controlled. In the first mentioned arrangement, assuming a wire 114 to carry a relatively high voltage to the lower contact spring f12, it will be evident that whenever a perforation in the sheet 51 registers with the extremity of contact spring f12, the associated conducting sleeve, which we shall assume is sleeve 62, will be at this relatively high voltage, whereas when this same or other perforation in the sheet is in register with contact spring f13 the sleeve will have a lower voltage, and when it is in register with the contact spring f14 the sleeve will have a still lower voltage. It will be understood that any one of these three voltages may be transmitted out through any one of the other contact springs f (associated with sleeve 62) to any particular piece of apparatus by having the perforation which coacts with that other contact spring f in predetermined angular relation to the aforementioned perforation which coacts with the selected one of the contact springs f12, f13 and f14 at that particular instant. This arrangement enables the different voltages to be transmitted selectively out through the other contact springs f over any number of separate control circuits, simultaneously or in any timed relation. In the modified arrangement referred to, where the sleeve 62 always has a constant potential, the arrangement of resistance connected contact springs f12, f13 and f14 is connected through wire 114 with the apparatus to be controlled, and when the perforation or perforations pass under these contact springs different voltages are transmitted out over said wire 114. 35

Figure 8 illustrates a modified embodiment of controller unit C which differs from the preceding embodiment principally in the use of a relatively long tape or sheet 51a which travels over two spaced drums 32 and 32a. The drum 32a may serve merely as an idler. The greater length of tape or sheet 51a in this embodiment enables a longer cycle of events to be established in the automatic operation of the apparatus. In every other respect the relation of the drum 32 and 45 contact fingers f may be the same as in the embodiment previously described. The manually controlled keyboard K may or may not be employed, as desired. 50

In Figure 9 I have illustrated still another construction of controlling unit C in which the control functions are changed by removing and variously positioning small contact elements receivable in perforations in the drum. The drum, designated 32b, has peripheral rows of uniformly spaced holes 121 therein. In one embodiment of this construction, the drum is a metallic conducting element and the contact springs f are constantly spaced from the surface of each sleeve 61—64, so that electrical connection is established 60 between said sleeves and their respective contact fingers through conducting contact elements 122 which are inserted in the holes 121 and which engage the contact fingers. The contact elements 122 may be of various shapes, such as U- 65 shaped pieces which afford a relatively long contact interval and which may be arranged end to end for continuing the contact interval for as long as desired, and also comprising small pins for short contact intervals. In another embodiment of this construction, the contact springs f may be arranged in pairs, consisting of inner and outer springs, and the elements 122 would then press the inner spring of each pair backwardly against the outer spring to close the control cir- 70 75

- cuit. In such embodiment the drum may not be energized, or it might be energized to establish a preliminary circuit through the inner spring before the two springs are pressed together.
- 5 While the cylinder type of controller unit is preferable, it will be evident that my invention may be practiced with a disc type of movable member, wherein the flat face of the disc is covered with a sheet of paper or the like provided 10 with the circuit closing perforations.
- I shall now describe my improved track equipment which cooperates with the controller unit C in effecting the desired automatic control of a toy train system.
- 15 In Figures 10 and 11, I have illustrated an improved construction of control track section which can be used advantageously with the prior types of remote-control, reversible motor, locomotives. In these prior locomotives the motor circuit is 20 reversed through the action of a relay mounted in the locomotive. The operation is such that successive impulses or circuit closures in the current supply to the locomotive actuate this relay, whereby the initial reestablishment of the circuit 25 will result in the locomotive reversing its travel, and two successive circuit closures are required to make the locomotive resume its previous direction of travel. The two sections of track illustrated in Figure 10 correspond to the sections 30 CS1 and CS2 shown in the lower portion of side track illustrated in the typical layout of Figure 1. The control section CS2 is a typical "dead" section wherein the outside ground rails r1 and r2 remain at a constant ground polarity but the 35 third rail r3'' is electrically insulated from the third rails of the track sections at each end thereof. The adjacent ends of the two third rails may have an air gap therebetween, or a short insulating pin 126 may connect the two rails. In 40 the common use of this type of control section CS2 a wire is extended from a control point to the isolated third rail of this track section. When the locomotive runs on to this track section and finds the isolated third rail r3'', dead the locomotive stops, but can be set into motion at any 45 time by again energizing this third rail through the separate wire extending thereto. From what has been said above, it will be seen that when the third rail r3'' is again energized, the impulse 50 of current will throw the relay switch in the locomotive for causing the locomotive to travel backwardly. If it is desired to have the locomotive resume its forward direction of travel, it is necessary, according to the prior practice, to 55 transmit two impulses or circuit closures, and the first impulse must be very short, otherwise the locomotive may travel backwardly an objectionable distance. This first impulse results in additional complication for automatic control, and 60 sometimes causes a movement of the locomotive which does not simulate actual practice. I have avoided such difficulties by providing a novel control track section CS1 which cooperates with the track section CS2 in automatically predetermining 65 the position of the relay switch when the locomotive rolls upon the "dead" section CS2. This improved control section comprises a short control contact 128 which is associated with the third rail r3 of section CS1, preferably at a point 70 in proximity to the dead section CS2. This control contact 128 may be built into the section CS1 by notching out a portion of its third rail r3 and mounting the contact 128 in the notched out portion, in insulated relation to the remainder 75 of the third rail; or this control contact may consist of a metallic clip, of inverted U-shape, which is placed over the third rail with a layer of insulating material 129 interposed between the clip and the third rail. Rivets or screws 131 joining the side portions of the clip to the web portion of the rail are also insulated from the rail. When the control contact 128 is thus applied in the form of a clip it is desirable that the third rail r3 be provided with sloping rises 133, 133 to form a substantially smooth sloping 10 surface for the contact roller of the locomotive to travel over. The short length r3' of the third rail r3 between control contact 128 and section CS2 is of the same continuous polarity as the main body of the third rail r3 of section CS1. 15 A wire 137 extends from the control contact 128 back to the control unit C. The contact rollers of a typical locomotive are indicated at 138 and 139, there usually being two of these rollers mounted on supporting members 141, generally in 20 the form of spring arms, or arms having pivotal mounting for yieldably holding the rollers down on the third rails of the track sections.
- Assuming the locomotive to be traveling in the direction indicated by the arrow, the control functions will be exercised primarily through the contact relations established with the trailing roller 138 because the leading roller 139 will be on the dead section CS2 while current is still being conducted through the trailing roller 138. If it 25 is desired that the relay switch of the approaching locomotive be thrown to a position to cause the locomotive to reverse after the locomotive has rolled upon the dead section CS2 and that section is later energized, then in that event the control 30 contact 128 is energized through the wire 137 to have the same polarity as the third rail r3 of control section CS1. Hence, there will be no break in the continuity of the current supply to the relay switch as the roller 138 travels over the control 35 contact 128 and over the end section r3' of the third rail, the only break in the current continuity being when the trailing roller 138 rides upon the third rail r3'' of the dead section CS2. Thereupon, when the third rail r3' of the dead section is 40 later energized by a single closing of the circuit, the relay switch will be thrown to cause the locomotive to reverse its direction of travel. If, on the other hand, it is desired that the relay switch 45 of the approaching locomotive be thrown to a position causing the locomotive to resume its former direction of travel after the locomotive has rolled upon the dead section and that section is later energized, then in that event the current supply through wire 137 is interrupted and hence 50 when the trailing roller 138 rides upon the control contact 128 the current supply to the relay switch is momentarily interrupted. The control contact 128 is of such short length that the locomotive 55 will not stop at this point but will continue to coast toward the dead section. After passing over the deenergized control contact 128, the roller 138 comes in contact with the terminal portion r3' of the third rail r3, thereby reenergizing the relay switch and the motor for but an instant— 60 followed immediately by the deenergization of the relay switch and motor when the roller 138 rides upon the third rail r3'' of the dead section CS2. The short length of the energized end section r3' prevents the moving locomotive from stopping 65 and then starting up in the opposite direction on this section r3'. When the locomotive comes to rest on the dead section CS2, its relay switch has now already received one current impulse from 70 this end section r3' and hence when the dead section r3' 75

tion is again energized this second impulse will result in the locomotive resuming its forward direction of travel. It will thus be seen that by energizing the control contact 128, or deenergizing the same, prior to a locomotive traveling over this contact onto the dead section, the relay switch in the locomotive can be placed in either desired position, whereby when the third rail r_3'' of the dead section CS2 is later energized the locomotive can be caused to travel either forwardly or backwardly as desired, without the necessity of first starting it in one direction in order to throw the relay switch, then interrupting the circuit, and then closing it again in order to have the locomotive resume its original direction of travel. Figure 1 illustrates how the control wires 137 from each of these control track sections CS1 extend to appropriate contact fingers f at the controller device C.

In Figure 12, I have illustrated an improved electrically operated track switch. The entire switch assembly corresponds to one of the track switches S1, S2, etc. of Figure 1, and comprises a base plate 144 having mounted thereon the grounded and third rail sections r_{11} , r_{12} and r_{13} of a through track and the grounded and third rail sections r_{14} , r_{15} and r_{16} of a switch track. A switching frog 151 is pivotally mounted at 152 on the base plate and carries shiftable rails 153, 153' which are adapted to be oscillated between open and closed positions of the track switch. An electromagnetic unit is diagrammatically indicated at 154, comprising two spaced U-shaped electromagnets 155, 156 and an armature 157, which is adapted to be attracted toward one or the other of said electromagnets. An operating rod 159 extends from the armature 157 and is suitably guided for guiding the motion of the armature. This operating rod may have a rack and pinion, link or any other suitable type of operating connection with the frog 151; in the arrangement illustrated the frog has an arm 161 extending therefrom having a slot 162 therein in which engages a pin 163 projecting from the operating rod 159.

The motion of the frog 151 is arranged to throw an electrical control switch generally indicated at 165. Said control switch comprises a pivotally swinging contact arm 166 which is adapted to engage alternately with two stop contacts 167 and 168. The contact arm 166 is arranged to have a snap motion so that it is always in engagement with one or the other of the contacts 167 or 168, depending upon the position of the switch frog 151, such being provided for in the illustrated arrangement by a biasing spring 171 which is adapted to swing across the pivotal center of the contact arm 166. When the switch frog is in the position illustrated, or in proximity to this position, the contact arm 166 is in engagement with the contact 168, and when the switch frog is in the other position, or in proximity to that position, the contact arm 166 is in engagement with the other contact 167. Any suitable operating linkage may be arranged to throw the contact arm 166 correspondingly with the movement of the switch frog; in the illustrated arrangement I have shown the biasing spring 171 as being connected to the switch frog to be carried from one side to the other of the pivotal center of the contact arm 166.

A wire 174 electrically connects the contact arm 166 with an insulated section r_{17} which is interposed in a portion of either one of the outer rails r_{11} or r_{12} at a point in the track length leading toward the open end of the switch, i. e., at a

point where, with a train approaching the switch from right to left, the wheels of the train will roll upon the insulated track section r_{17} before arriving at the switch. This insulated section is insulated from the rail r_{11} and from the base plate, and may be interposed in either the outer rail r_{11} or the inner rail r_{12} . If desired, a resistance 176 may be interposed in the connection leading from the insulated rail section r_{17} to the contact arm 166. Wires 177 and 178 extend from the stop contacts 167 and 168, respectively, to the windings 155' and 156' on the electromagnet cores 155 and 156. The other ends of both windings are multiplied to a wire 181 which connects with the other track polarity, i. e., the third rail polarity, such being effected by extending said wire to any one of the third rail sections r_{13} or r_{16} of the track switch unit, or extending said wire to any other control point where third rail polarity may be impressed on said wire.

The above described track switch construction has been devised primarily to prevent the derailing accidents which so frequently happen in these toy electric trains in the case of a train approaching the entering end of a switch, i. e., in the arrangement illustrated this would be a train traveling on the straight line section from right to left. These derailing accidents arise when a portion of the train has passed over the switch and taken its intended direction of travel either along the main line or off on the side line, and the vibration of the passing cars, particularly in a rapidly moving train, has caused the switch to shift slightly, with the result that the trailing cars near the end of the train strike the switch point and are derailed or are deflected onto the opposite section of the track, with consequent derailing of part or all of the train and also the possibility of broken couplings. These accidents come about principally because of the relatively small operating energy available for throwing the switch in the ordinary remote-control, electrically-operated type of switch. The general practice is to energize a particular electromagnet or solenoid to throw the switch to its desired position and then to interrupt the energization of said solenoid or electromagnet. Reliance is then placed on small spring detents or snap projections for holding the switch in the position into which it has been thrown. Obviously, these spring detents cannot be very strong, otherwise the other solenoid or electromagnet would be incapable of releasing it from said detent for throwing the switch in the other direction. Consequently, the vibration of a rapidly traveling train passing over the switch is very likely to vibrate the switch loose from these detents, with the resulting derailment of a portion of the train. Such is avoided in the present construction by the above described mechanism which provides a train-controlled circuit operating to magnetically hold the track switch in either of its previously thrown positions. This is brought about by reason of the fact that as soon as a train approaches the entering end of the switch, its wheels and axles establish a bridging shunt from one of the outside grounded rails r_{11} or r_{12} , as the case may be, to the insulated section of outside rail r_{17} , thereby transmitting ground polarity to said insulated section r_{17} . Assuming the switch to be in the position illustrated, this ground polarity will then be transmitted through resistance 176, wire 174, contact arm 166, contact 168 and wire 178 to the elec-

tromagnet coil 156'. The other end of said electromagnet coil has third rail polarity constantly impressed thereon through wire 181. Consequently, when this coil receives ground polarity 5 from insulated track section r17 it is energized and thereby caused to attract the armature 157 for forcibly holding the track switch in this position, against the vibration of a passing train. After the wheels of the last truck have traveled 10 off the insulated track section r17 and beyond the switch the circuit through the coil 156' is automatically opened. When the switch has previously been thrown to its other position for directing the train onto the side track, the contact arm 166 has also been thrown concurrently therewith, placing said contact arm in engagement with stop contact 167. Hence, when the front wheels of the first truck of the train approaching the entrance end of the switch pass 15 on to the insulated rail section r17 a circuit is established through contact arm 166, contact 167 and wire 177 with the other electromagnet 155', which is thereby energized for attracting the armature 157 so as to forcibly hold the switch in 20 this latter switching position, against the vibration of the passing train. The insulated rail section r17 extends in one direction to within fairly close proximity to the switch point of the frog 151 so that the circuit will be maintained through 25 said insulated rail section up until the wheels of the last truck have passed beyond the switch point of the frog—either in traveling along the straight line track section or in traveling on to the side track. This insulated rail section r17 30 is extended in the opposite direction for a sufficient length so that at all times in the travel of a train over this track section some one of the pairs of wheels will be rolling on said insulated section r17 for maintaining the above described 35 control circuit. It will be observed that this relation of an insulated rail section r17 in only one of the outer grounded rails does not interrupt the circuit of an electric motor in the locomotive because ground polarity can always be supplied to 40 the locomotive through the opposite outer ground rail.

Practically no derailing difficulties are encountered in the case of trains approaching the other or rear end of the switch, either along the main 50 line section or the side track section, because the flanges on the car wheels function to cam the switch frog into the desired position for continued travel of the train.

If desired, the above described control apparatus including the electromagnets 155, 156 and armature 157, may be utilized as an independent control element, separate and apart from the electromagnetic actuating devices which are commonly employed in these remote-control, electrically-operated switches for toy trains. However, my improved apparatus is capable of performing the dual function of throwing the switch into one position or the other in response to the actuation of a remote control, and of automatically holding the switch in either of its thrown 60 positions in response to the control circuit established by the passing train. As illustrating the apparatus in this dual function, I have diagrammatically illustrated extension control wires 65 183 and 184 extending from the wires 177 and 178, respectively, which extension wires connect with appropriate contact fingers f cooperating with the ground polarity sleeve 61 on the controller unit C. It will be evident that when the 70 corresponding perforations 51' in the insulating

sheet 51 move under these respective contact springs the electromagnet coils 155' and 156' will be appropriately energized for throwing the switch in one direction or the other in the cyclical operation of the system—and that after the energization of either one of these electromagnet coils has been discontinued by the movement of the perforation beyond the contact finger f associated with that particular coil, the coil can still be later energized by a train approaching the entering 10 end of that switch, for the purpose of magnetically holding said switch in the position into which it has been thrown. The resistance 176 may, if desired, be included in the wire 174 so that the potential which can be transmitted to either 15 one of the coils 155', 156' from the insulated track section r17 will always be less than the potential which can be transmitted to the coils from the control unit C. This would enable the automatic control unit C to throw the switch into an opposite position, even when a train has come to rest 20 on the switch approaching part of the straight line track, with the wheels of the front locomotive or car resting on the insulated rail section r17. By virtue of the resistance 176, a higher 25 potential can be transmitted to the other coil for throwing the switch into the opposite position, notwithstanding the fact that the opposing coil is already energized at this time. In this regard, the various arrangements which I have previously described for transmitting different voltages from the control unit C might also be employed for transmitting higher voltages to the coils 155', 156' of the track switch than would be transmitted from the rail section r17, even with 30 out the resistance. All of the track switches S1, S2, S3, etc. illustrated in the diagrammatic layout of Figure 1 are preferably of the construction which I have just described.

My invention also includes improvements in toy 40 electric locomotives characterized by an improved electric motor and characterized by improved control apparatus, whereby the locomotive may be caused to reverse its direction of travel or to travel at different speeds, in response to control functions exercised by the controlling unit C.

Referring to Figure 13, I have illustrated one embodiment of my improved locomotive provided with a reversible, variable-speed, alternating current motor of the shaded-pole induction type. 50 This motor, which is designated 186 in its entirety, has any conventional driving connection with the locomotive wheels, such as through a pinion 187 on the rotor shaft which drives through a gear train 188, 189, 190 to the wheels 191. The motor comprises a laminated field structure 192 and a squirrel cage rotor 193. The rotor revolves in a circular gap or rotor space 194, and the field structure either completely, or almost completely circumscribes this rotor space, having portions 55 192a and 192b of the laminated field structure extending across from side to side above and below the rotor space. If desired, very small gaps may be provided in these extension portions 192a and 192b. In the reversible type of motor, the portions of the stator structure adjacent to the rotor space 194 are slotted to accommodate four shading coils 195, 196 and 197, 198. The two shading coils 195 and 196 are cross connected as a pair by the wire or conductor diagrammatically indicated at 201, and the two coils 197 and 198 are likewise cross connected as a pair by a conductor diagrammatically indicated at 202. Rotation of the rotor in one direction is obtained by connecting the outer ends of shading coils 195 and 196 70 75

in series, and rotation of the rotor in the other direction is obtained by interrupting this series connection and connecting the outer ends of the other two shading coils 197 and 198 in series. The 5 field winding is indicated at 204, and for a variable speed motor this winding comprises two sections 204a and 204b. For high speed operation only the one section 204a is energized, and for low speed operation both sections 204a and 204b 10 are energized.

This type of motor is much more efficient and has much more torque than the conventional commutator type of alternating current motor now used in toy electric locomotives. All 15 commutator trouble is avoided in this improved type of motor, particularly the heavy arcing and sparking which is very destructively present at the commutator brushes of the older type motors when such motors are suddenly reversed under full load. Moreover, this new type of 20 shaded pole induction motor has an almost constant selected speed through a wide range of load, which is a particularly desirable feature in the present automatically controlled despatching system wherein a substantially constant train speed enables closer and more reliable synchronization to be obtained in automatic cycle operation. With the older commutator types of 25 motors there was always the pronounced objections of trains virtually running away on the straight-away sections of the track and stalling on the curved sections, which is sometimes so pronounced as to make window display work more 30 harmful than helpful. A further advantage of this new type of induction motor is the fact that the rotor speed is not appreciably affected, or is affected very little, by moderate voltage changes. Hence, these voltage changes can be utilized to 35 effect the reversing and variable speed controls 40 in the locomotive without affecting its performance.

Referring now to these improved controls as I have illustrated them in Figure 13, the reversing control is preferably effected by a swinging contact arm 212, which is pivotally mounted at 45 213 on a bracket 214 stationarily secured either on the field structure of the motor or on some supporting member adjacent thereto. In the illustrated arrangement, the arm 212 is arranged 50 to be responsive to leakage flux emanating from the field structure 192, and hence this arm is disposed in proximity to said field structure where it will be within the influence of said leakage flux, preferably extending down adjacent to 55 one of the side limbs of the field structure. The swinging end of said arm bears contacts 215 on opposite sides thereof, and in the normal position of the arm it is swung in a direction away from the field structure, so as to bring the outer 60 of its contacts 215 into engagement with an outer stationary contact 216. When the leakage flux increases to a predetermined value, as a result of a higher voltage applied to the field winding 65 204, the arm 212 is attracted toward the field structure, thereby bringing the inner of its contacts 215 against an inner stationary contact 217. The arm may normally be held in its outward 70 position against the outer stationary contact 216 by a light spring, although I find that a more easily adjusted construction is to make the arm in the form of a bell crank lever and provide a weight 219 on the other lever arm, which weight is slidably adjustable along said 75 arm, or which can be otherwise adjusted by the

addition or removal of washers or like weighting elements. In such construction, the lower portion of the bell crank, which is intended to be responsive to leakage flux, is of a magnetic metal, whereas the upper portion of the bell crank, 5 designated 212a, is of non-magnetic metal so as not to be responsive to flux. A wire 221 connects outer contact 216 with the outer end of shading coil 196, and a wire 222 connects inner contact 217 with the outer end of shading coil 198. The 10 outer ends of the other two shading coils 195 and 197 are both grounded, as by a connection 223 grounded to the field structure 192. The swinging contact arm 212 is likewise grounded, as through the pivot 213 and bracket 214 which 15 is secured to the field structure.

In describing the operation of this reversing control apparatus, it will be assumed that the locomotive motor is of a size and design intended normally to operate on approximately 25 volts, 20 this figure being selected solely as an arbitrary voltage for purposes of illustration. The adjustment of the weight 219 on the pivoted contact arm 212 is such that as long as 25 volts are supplied to the motor said contact arm will remain in its outer position against contact 216, in which position the two shading coils 195 and 196 are connected together in series through ground afforded by the field structure 192. At this time it is only these two coils 195 and 196 25 which are operative to shade or influence the flux, and this results in a direction of rotation of the rotor which drives the locomotive forwardly. When it is desired to reverse the locomotive, 30 the effective voltage is increased to approximately 30 volts, such being accomplished by one of the voltage changing arrangements previously described at the control unit C. The increased amount of leakage flux emanating from the field structure at this higher voltage causes the contact arm 212 to be attracted toward the field structure, thereby breaking circuit at the contact 216 and making circuit at the contact 217. This open circuits the two shading coils 195, 196, 35 and close circuits the other two shading coils 197, 198 through the ground afforded by the field structure. This reversed shaded relation causes the rotor to revolve in the opposite direction, for reversing the direction of travel of the locomotive. 40

To avoid the effects of inertia, it is preferable to dispose the contact 216 (which contact establishes forward direction of travel) at the side of the contact arm 212 which is rearward with respect to the forward direction of travel of the locomotive. Hence, in the operation of starting the locomotive forward after each stop, any inertia in the arm 212 will cause it to press all the harder against contact 216, instead of possibly vibrating away from said contact such as otherwise might happen if this forward direction contact were at the front or opposite side of the arm 212. The disposal of the rearward direction contact 217 at the front side of the swinging contact arm 212 also has a correlative advantage when the train is starting in a reverse direction, in that the inertia set up in said arm, in starting in said reverse direction, aids in holding the contact arm 212 against said front contact 217. In this regard, the substantially horizontal disposal of the 55 arm portion 212a on which the weight 219 is mounted practically eliminates any effect of the starting inertia on this weighted end of the control arm.

Referring now to the control apparatus which 60

governs the speed of the locomotive, such comprises a relay 225 mounted in the locomotive and including a coil 226 and an armature 227. One end of the relay coil 226 is grounded to the locomotive to receive ground polarity from the outside rails r_1, r_2 through the wheels, and the other end of said coil is connected to the contact rollers 188, 189 to receive the third rail polarity. Hence, it will be seen that said coil is shunted across the track potential at all times so as to be responsive to changes in track voltage. Third rail polarity is transmitted through wire 231 to one end of the field coil 204, and ground rail polarity is selectively transmitted through wires 232 and 233 either to the intermediate tap 234 or to the opposite end of the field coil. It will be understood that this relation might be reversed so that third rail polarity is transmitted through the wires 232 and 233. The armature 227 is continuously connected to ground polarity, and is urged outwardly away from the magnet coil 226 by an adjustable spring 236. The wire 232 terminates in a stationary contact 237 disposed at the front side of said armature, and the wire 233 terminates in a stationary contact 238 disposed at the back side of said armature.

Assuming that 25 volts is the normal operating voltage for the locomotive, the spring 236 is adjusted whereby the magnetic pull produced by that voltage holds the armature 227 against the front contact 237. This results in only one section 204a of the field coil being energized, which results in a relatively high speed rotation of the rotor. The relay is so adjusted that when the track voltage is lowered to 20 volts, as by the functioning of one of the previously described voltage changing arrangements at the control unit C, the armature 227 will drop back against its back contact 238, whereupon both sections of the field coil are energized. This results in a slower speed of rotation of the rotor, such seemingly following from the higher impedance of the two sections of the coil.

Summarizing these control functions obtainable by voltage change, it will be seen that at 25 volts track voltage the locomotive will travel forwardly at what may be regarded as its normal or high speed. At 30 volts the locomotive will change its direction of travel. At 20 volts it will travel forwardly at a slower speed. These same control functions can be obtained in the lower voltage locomotives, where the three voltages would be substantially in the order of 12, 15 and 18 volts. It will be understood that the relation of the different voltages to the different controls may be varied from the relation above described. Also, if desired, the contact arm 212 which controls the reversing function might be made responsive to a relay coil, like the coil 226, shunted across the track voltage; or the armature 227 controlling the locomotive speed might be arranged to respond to flux leakage from the field structure 192, like the contact arm 212.

In the present stage of development of these shaded-pole induction motors, more power is available from such motors of the non-reversible type than is obtainable from such motors of the reversible type. The non-reversible type has only two portions of its stator structure shaded, comparable to the shading produced by only the two coils 195-196 or 197-198, see Figure 15. In Figures 14 and 15, I have illustrated how this greater power may be obtained, while still retaining the feature of being able to reverse the locomotive. In Figure 14 two of these motors

186A are disposed back to back in the locomotive, with their rotor pinions 187 connecting through separate gear trains 188-190 to the wheels 191 at opposite sides of the locomotive. The energization of one motor drives the locomotive in one direction, and the energization of the other motor drives the locomotive in the opposite direction. The motors are selectively energized by a voltage controlled relay 244 which has its winding connected in shunt across the third and ground rails. One track voltage operates through said relay to energize one motor, and another track voltage operates through said relay to energize the other motor, such being accomplished through the functioning of the relay contacts in a manner which will be clearly understood from the diagrammatic illustration and from the preceding description. As an alternative arrangement, instead of having the two rotors drive through separate gear trains, a direct cross-connecting mechanical coupling can be established between the two rotors so that they both drive down through one gear train irrespective of which motor is operating. When one of these motors is deenergized the retarding force opposing rotation of the rotor in either direction is so small as to be almost negligible.

Figure 15 illustrates another alternative arrangement wherein the two motors 186A are arranged to drive the wheels of separate trucks of the locomotive. The shading coils on these two motors are in reversed relation so that when one motor is energized the locomotive will travel in one direction, and when the other motor is energized the locomotive will travel in the opposite direction. A similar voltage controlled relay selectively energizes the motors in response to changes in track voltage.

In Figure 16, I have illustrated another embodiment wherein a single motor is selectively coupled to the locomotive wheels in a reversible driving relation or in a speed changing relation, through the actuation of a magnetically responsive clutch. In this construction the projecting end of the rotor shaft 193a has an oppositely tapered double-clutch element 251 splined on said shaft for shifting movement thereon. Rotatably mounted on said shaft on opposite sides of this driving clutch element are two driven clutch elements 252 and 253, which have female conical surfaces to be engaged by the male conical surfaces of the driving clutch element. These driven clutch elements are connected with spur pinions 254 and 255, respectively. Supporting this portion of the rotor shaft are two thrust collar bearings 256 disposed on the outer sides of the pinions 254, 255. A light compression spring 258 coiled about the shaft 193a normally forces the driving clutch element 251 over into engagement with the outer driven clutch element 252. The pinion 254 has driving connection with the locomotive wheels through a gear train, the parts of which are indicated collectively at 261, and the other pinion 255 has driving connection with the locomotive wheels through a separate gear train, the parts of which are indicated collectively at 262.

The body of the driving clutch element 251, or the major portion thereof, is composed of magnetic material, and this clutch element is disposed sufficiently close to the field structure 192 of the motor as to be responsive to the leakage flux therefrom. The driven clutch elements 252, 253, the pinions 254, 255, and such other gears and parts as may be within this zone of leakage flux, are composed of non-magnetic metals so that the

entire leakage flux at this side of the motor is effective on the magnetic driven clutch element 251. The pressure of the spring 258 is proportioned so that at a normal or relatively low voltage this clutch element will be held in driving engagement with the driven clutch element 252, and at a higher voltage the greater concentration of leakage flux will magnetically attract the clutch element 251 over into engagement with the inner 5 driven clutch element 253. As previously remarked, the entire body of the magnetic clutch element 251 may be composed of magnetic material, or only a portion thereof; or, if desired, this element might be composed of a molding plastic 10 material and magnetic iron dust, which composition will give high magnetic attraction, a good wearing surface for the clutch engaging surfaces, and still avoid any excess heating which might otherwise result from eddy currents. 15

20 The differentiation between the gear trains 261 and 262 may be for the purpose of reversing or for obtaining different speeds. That is to say, the number of gears in one train may be different from that in the other for driving the locomotive 25 in one direction through one train and driving it in the other direction through the other train; or, the number of gears in the two trains may be the same but with different gear ratios in the two trains so as to drive the locomotive at one speed 30 through one train and at a different speed through the other train. As an alternative construction, a separate solenoid or electromagnet, responsive either directly to voltage change or controlled by a voltage responsive relay, may be arranged for 35 mechanically shifting the driving clutch element into and out of engagement with the respective driven clutch elements.

In Figure 17 I have illustrated another modified embodiment wherein the above mentioned 40 solenoid type of operation is obtained by employing the rotor of the electric motor as the shiftable solenoid core. The construction of the electric motor may be of the same general type as illustrated in Figures 13 or 15, with the exception that the rotor 193 is arranged for endwise shifting movement in the rotor space 194 of the stator. I have found that when the rotor is slightly displaced endwise from its rotor space 50 the lines of flux exert a force on the rotor tending to pull it back to a symmetrically disposed position in the rotor gap. This force, tending to restore the rotor endwise to a symmetrically disposed position, is an accurate measure of the voltage impressed on the motor and hence this force 55 can be used to effect the shifting of clutch mechanism, in response to a change of voltage transmitted through the track.

In the illustrated arrangement, the rotor 193 is fixed to its shaft 193a and the shaft is arranged 60 for endwise sliding movement in suitable bearing supports, which bearing supports are illustrated more or less diagrammatically by the side plate 266 and by the side portions 267 of the housing 268 enclosing the clutch mechanism. A suitable 65 force is normally exerted on the rotor tending to shift the latter to a slight distance out of the rotor space, as illustrated in the drawings. If the axis of the rotor is disposed substantially vertically the weight of the rotor itself may represent 70 this force, or, if the axis of the rotor is horizontal, a bell crank lever 271 may be pivotally mounted on the side plate 266, with one arm of said lever pressing against the end of the rotor shaft 193a and with the other arm of said lever having a 75 weight 272 adjustably mounted thereon. The

driving clutch element 251a has its hub fixedly pinned to the rotor shaft 193a so as to rotate and shift with said shaft. The two driven clutch elements 252a and 253a are rotatably mounted on said shaft, with their respective spur pinions 254 and 255 secured to said driven clutch elements to rotate therewith. The clutch construction may be arranged to have conical clutch surfaces, as illustrated in Figure 16, or the driving clutch element 251a may have rings 251b of friction material secured to opposite sides thereof for engaging with the driven clutch elements. The gear trains 261 and 262, extending respectively from the spur pinions 254 and 255, may be arranged for reversing the locomotive or for obtaining different speeds, as pointed out in connection with the embodiment of Figure 16.

It is also within the scope of my invention to combine either of the electrical controls of Figure 13 with the constructions illustrated in Figures 14, 15, 16 and 17. For example, assuming the relation of the two motors 186A of Figures 14 and 15 to be for the purpose of securing a reversible drive, the feature of selective speeds may also be combined therewith by providing the forward driving motor with a two-section stator winding 204a-204b and providing a voltage-controlled, speed-selecting relay 225 with its contacts 237 and 238 connected to the two sections of the stator winding of that 30 motor, so that one voltage will result in backward operation, another voltage will result in forward operation at one speed, and still another voltage will result in forward operation at a different speed. This is clearly illustrated in Figure 15. Likewise, in the case of the single motor construction of Figures 16 and 17, if the differentiation between the gear trains 261 and 262 is for the purpose of a reversible drive, then the feature of selective speeds may also be combined therewith by having the stator winding of the single motor in two sections, and providing a voltage-controlled relay 225 for controlling the energization of the winding sections selectively, which relay will respond to a third voltage separate from those two voltages which determine whether the shiftable clutch element is in one position or the other. Conversely, if the differentiation between the gear trains 261 and 262 is for the purpose of speed selection, then a reversible drive may be obtained by providing the motor with four shading coils 195-198 and employing a swinging contact arm 212 responsive to the leakage flux produced by a third voltage, for controlling through the contacts 215, 216, 217 which pair of shading coils shall be energized, substantially as shown in Figure 13.

In Figures 18 and 19 I have illustrated another modified construction of toy locomotive wherein the shifting movement of the rotor within the locomotive motor performs switching operations governing certain circuits of the motor. The rotor shaft 193a has its end extending outwardly beyond both side plates 266, and the switch parts are preferably disposed concentrically of this rotor shaft on the outer side of one of said plates. Said switch parts include a series of rings or washers, comprising an inner insulating washer 273, a conducting washer 274, an insulating washer 275, a conducting washer 276 and an insulating washer 277. These washers are maintained in assembled relation on the rotor shaft by any suitable bracket structure 278 having attachment to the motor frame. The rotor shaft has a reduced portion 193c, a collar por- 75

tion 193d, a reduced portion 193e and an enlarged end portion 193f. Thrusting means in the form of a spring 279 normally tends to hold the rotor shifted to the left, in the position illustrated. 5 In a motor designed for operating at a normal voltage in the neighborhood of 25 or 30 volts, the rotor would be in the position illustrated when the motor was receiving its normal or relatively low voltage, say, 25 volts. At this 10 time, the contacting collar portion 193d is in engagement with the conducting washer 274 and is establishing a ground connection from said washer 274 to the frame of the motor through the rotor shaft bearings. The spring thrusting 15 means 279 is so adjusted that when the voltage is increased a predetermined amount, say, to 30 volts, the increased flux density acting on the rotor and tending to reduce the reluctance of the rotor gap, will cause the rotor to be shifted 20 over to its dotted line position for placing the contacting collar portion 193d in engagement with the other conducting washer 276. This will interrupt the ground connection which previously existed between the washer 274 and the 25 motor frame and will establish a different ground connection from the washer 276 to the motor frame. If desired, the thrusting means 279 might consist of a weighted arm, as shown in Figure 17, or might consist of a biasing spring 30 arrangement, similar to an over-center snap spring, but arranged so that the travel does not quite pass over center, whereby return motion is assured.

Referring to the circuit connections illustrated, 35 the conducting washer 274 is electrically connected with the two shading coils 195 and 196 so that when the washer 274 is grounded a circuit will be completed through these two shading coils for causing the motor to operate in the forward direction. Likewise, the other conducting washer 276 is electrically connected with the other two shading coils 197 and 198 so that when this washer is grounded a circuit will be completed through the latter shading coils for 40 causing the motor to operate in the reverse direction. While it is preferable to employ this switching arrangement for effecting the reverse of the motor, it will be understood that, if desired, the conducting washers 274 and 276 may 45 be electrically connected with the stator winding to effect speed changes. In each of the preceding constructions wherein reversing of the locomotive is brought about by the use of the two pairs of shading coils 195, 196 and 197, 198, 50 the shading coils for causing reverse direction of travel may be so arranged that the reverse speed is only a fraction of the forward speed.

In Figure 20 I have illustrated a modified construction of toy locomotive characterized by a 55 differential action between the drive transmitted to the wheels at one side of the locomotive and the drive transmitted to the wheels at the other side. In the conventional construction of toy electric locomotive, the wheels at both sides always rotate at the same speed, and the tendency of these locomotives to jump the track when 60 rounding a curve is due, in a large measure, to the dragging action of the wheels on the outside of the curve and the accelerating action of the 65 wheels on the inside of the curve. I propose providing a differential action in a simple, inexpensive manner by employing a single motor structure 186 provided with two rotors 193b and 193c, both revolving in the same rotor gap and both 70 driven by the flux from the same stator winding.

These two rotors are each independently rotatable on the rotor shaft 193a, or one of said rotors is independently rotatable thereon. The rotor pinion 187 of each rotor drives down through an individual gear train 188, 189, 190 to the side wheel 191 at that side of the locomotive. These drive wheels 191 are capable of independent rotation, as, for instance, by having them rotatably mounted on a dead axle 191a, and the lower gears of the gear trains are attached directly to 10 said wheels, the illustration showing said gears connected to the wheels by sleeves. It will be evident that in this construction the two rotors deliver the same torque to the wheels at each side of the locomotive, but when the locomotive 15 is rounding a curve the rotor and wheels at the outside of the curve are capable of rotating at a higher speed than the rotor and wheels at the inside of the curve. This two-rotor construction can be embodied in an induction type of motor 20 such as I have previously described, or in the conventional commutator type of motor; in the commutator type of motor the two commutators, one individual to each armature or rotor, being preferably at the outer ends of their respective rotors. 25 While the above described construction having two rotors in a single stator structure is preferable, I also contemplate an improved toy electric locomotive wherein the differential action is obtained by using two separate motors each independently geared to the wheels at each side of the locomotive, substantially as represented by the two motors 186A in Figure 14. In such embodiment, the driving wheels 191 at opposite sides 30 would be capable of independent rotation and the two motors 186A would be wound or otherwise arranged for both driving the locomotive in the same direction.

Induction motors such as I have described in connection with Figures 13 to 20, inclusive, are 35 better adapted to toy locomotive work owing to their greater dependability, to their more uniform current consumption under varying loads, even down to the stalling point, and to their more uniform torque from starting to running speed. 40 In each of these respects, this induction type of motor is superior to the conventional commutator type of motor now used in toy locomotives. The characteristic of this induction type of motor to have comparatively small change of speed with 45 voltage changes, which is radically different from the characteristic performance of a conventional toy locomotive commutator motor, makes it entirely practicable to employ changes of voltage to bring about the different locomotive control 50 functions. I have illustrated the squirrel cage rotors of these induction motors more or less diagrammatically, but it will be understood that the cross-wise copper conducting bars may extend parallel to the rotor axis or may be slightly 55 inclined relative to the axis. While I prefer to employ the above type of induction motor in my improved toy locomotive for the reasons above set forth, my invention also contemplates the use of a self-starting synchronous motor in the locomotive, which motor will maintain a substantially constant selected speed independently of voltage change, or to employ an induction motor which will maintain a substantially constant speed through moderate voltage changes, etc., or to 60 employ a combination of the two for obtaining a high starting torque and in addition a constant speed characteristic.

In Figure 20 I have diagrammatically illustrated an improved arrangement for maintain- 75

ing the locomotive headlight burning while the locomotive is standing on a dead section of the track. This is accomplished by providing a headlight circuit extending back through the 5 series of cars, which circuit receives current from a live section of the track through a contact roller carried on one of the end cars. The locomotive headlight 281 comprises a bulb 282 which is mounted in a socket having one side grounded 10 to the locomotive frame so as to receive ground polarity from the outer ground rails. A wire 283 is connected to said socket or bulb to conduct third rail polarity thereto, and this wire extends rearwardly through the train of cars. In the 15 end car, or in one of the cars near the end of the train, this wire is electrically connected to an insulated contact arm 284 mounted on the car and carrying a contact roller 285 which rides on the third rails of the track sections. The wire 20 283 may extend in one piece from the headlight back to the contact arm 284, although in the preferred embodiment this wire is divided into sections 283a, one section individual to each car 286. Each section is suitably attached in the car and 25 has its ends extending into the end vestibules or over the end platforms of the car so as to have the wire section simulate the appearance of a signaling cord running through the car. The ends of adjacent sections 283a have tip connections 30 287 and 288 which can be readily coupled together. In the illustrated arrangement, the connecting tip 287 has a projecting pin end, and the connecting tip 288 has a socket for receiving this pin end. In the case of cars 286 provided with 35 contact arms and rollers 284 and 285 as standard equipment for lighting lamps within the cars, the wire section 283a of the end car may be connected to the third rail terminal of the light socket in that car, but the sections 283a in the front cars 40 of the train preferably have no connection with the light sockets of these forward cars, in order to prevent third rail polarity from being transmitted through the wire 283 to the third rail of the dead track section. It will be seen from 45 the foregoing that when the locomotive pulls up onto a dead section and stops, the end car of the train will in almost all cases still rest on a live section of the track and hence will transmit third rail polarity to the locomotive headlight. The 50 fact that the locomotive headlight remains illuminated, even with the locomotive stopped, adds greatly to the attractive appearance of the system.

Figure 1 illustrates one typical method of wiring all of the control parts of the system with the contact fingers *f* of the controller unit C. In this illustrated arrangement, all of the wires are supported on poles 291, which may represent telegraph poles, or high tension poles or towers. 55 Wires are extended from the various track sections T1, T2, etc., the track switches S1, S2, etc., the control track sections CS1, CS2, the semaphore signals 24, the crossing gate 25, the blinker signal lights 26, etc., all of which wires connect 60 with individual contact fingers *f* cooperating with the control drum 32. When the system is to operate with the conventional type of remote-control, reversible locomotive wherein the reversing function is performed by a relay within the locomotive 65 responsive to current impulses, the track layout will preferably embody control track sections CS1 having control contacts f12, each of which control contacts will be connected through wires 137 with contact fingers *f* associated with the 70 third rail sleeve 64 of the controller unit. This 75

use of the two control track sections CS1 and CS2 is exemplified in that portion of the track approaching the crossover 292 from the upper portion of the layout of Figure 1. In systems employing any of my improved types of reversible locomotives illustrated in Figures 13, 14, 15, 16, 17, 18 and 19, the control sections CS1 may, if desired, be dispensed with, since in the use of these locomotives the reversal is effected by voltage change rather than by sequence of current impulses. When using these improved types of locomotives it is only necessary to employ the control track sections CS2 having the insulated third rail sections r3' for stopping and starting the locomotives, three of these control sections CS2 5 being illustrated at the other three sides of the crossover 292. The wires 294 extending from the isolated third rails r3' of these "dead" sections CS2 may, if desired, be so connected with the controller unit C as to transmit two or three different voltages to the isolated third rails of their respective dead sections. The ability to transmit selective voltages to said dead sections CS2 enables speed changes to be obtained for slowing the locomotive down to a gradual stop and for accelerating the locomotive by selective speeds up to a running speed, thereby more closely simulating actual practice, and also enables the locomotive to be reversed on these control sections. For obtaining these voltage changes which, for 10 my improved types of variable speed, reversible locomotive, are approximately in the ratio of 20, 25 and 30 volts or 12, 15 and 18 volts as previously described, the wires 294 may each be connected in multiple to a contact finger *f* associated 15 with the sleeve 64, to a contact finger *f* associated with the sleeve 63 and to a contact finger *f* associated with the sleeve 62. As different performances 20 in the paper tape pass under these contact fingers, higher or lower voltages are transmitted out over that particular wire 294 to its 25 respective control section CS2. As an alternative arrangement, the varying voltages may be obtained by connecting each of these wires 294 with an individual set of resistance connected contacts f12—f14, as illustrated in Figure 7, or with 30 a contact finger cooperating with a sleeve which receives its voltage through such arrangement of resisted connected contact fingers f12—f14. In 35 most instances the third rails of track sections at 40 opposite ends of a control section will be connected by jumper wires 296 so that all of the third rails of the system, with the exception of those in 45 the control sections, will be connected together, but it is entirely within the practical adaptability 50 of my invention to have the third rails of each and every track section in the entire system insulated from every other third rail, with each of 55 these individual third rails provided with separate control wires leading to contact fingers *f* at 60 the controller device C. Moreover, according to my invention, it is entirely practicable to insulate one complete loop, side track, main track, or any other portion, from the remainder of the layout 65 so that in operating two or more trains one train on one portion of the layout may be operated at one speed or in one direction and another train on another portion of the layout may be operated at a different speed or in the other direction, the two insulated portions of the layout being 70 capable of receiving different voltages selectively from the controller unit C. 75

If the track switches S1, S2, etc. are energized by connecting third rail polarity to the outer ends of the electromagnet coils 155' and 156', then the 75

two control wires 183 and 184 are connected to contact fingers 7 associated with the conducting sleeve 64 of the controller unit, whereas if these coils are energized by ground polarity the two wires 183 and 184 are connected to contact fingers associated with the conducting sleeve 61. The same is true in the case of the semaphore signals, crossing gates, crossing lights and any other track accessories.

10 While I have illustrated and described what I regard to be the preferred embodiments of my invention, nevertheless it will be understood that such are merely exemplary and that numerous modifications and rearrangements may be made 15 therein without departing from the essence of the invention. It is clear that numerous broad features of my invention are also applicable to any similar toy train or toy car system which might employ overhead trolley wires instead of 20 a third rail, or which might be of the monorail type, and that, therefore, in the appended claims the reference to a "locomotive" shall be considered as including a toy trolley car or other electrically driven vehicle.

25 I claim:

1. In a toy electric train system, the combination of a track layout comprising first and second conducting members insulated from each other and supplying current to the trains, said 30 second conducting member including separately insulated sections, a source of alternating current supply, an automatic controller device comprising means for selectively transmitting current from said source of alternating current to the insulated sections of said second conductor at different time intervals in an automatic cycle, an alternating current motor operating said automatic controller device, said motor deriving its current from said source of alternating current 40 supply and running at a speed substantially predetermined by the frequency of said source of supply, and a toy car traveling on said track layout, said car comprising an alternating current motor also running at a speed substantially 45 predetermined by the frequency of said source of alternating current supply, whereby synchronous relation can be maintained between the travel of said car and the timed energization of said insulated sections.

50 2. In a toy electric train system, the combination of a track layout comprising first and second conducting members insulated from each other and supplying current to the trains, said second conducting member including therein a plurality of separately insulated sections, a source 55 of alternating current supply, an automatic controller device comprising a plurality of contacts, a rotatable member and a sheet of insulating material on said rotatable member having perforations therein through which said contacts can engage said rotatable member for selectively transmitting current from said source of current supply to the insulated sections of said second conductor at different time intervals in an automatic cycle, an alternating current motor operatively connected to drive said rotatable member, said motor deriving its current from said source of alternating current supply and running at a speed substantially predetermined by the 60 frequency of said source of supply, and a toy car traveling on said track layout comprising an alternating current motor also running at a speed substantially predetermined by the frequency of said alternating current supply, whereby substantially synchronous relation can be maintained 75

between the travel of said car and the timed energization of said insulated sections.

3. In a toy electric train system, the combination of a track layout comprising first and second conducting members insulated from each other and supplying current to the trains, said second conducting member including therein insulated sections, track switches associated with said track layout, track signals associated with said track layout, a source of alternating current supply for energizing said conducting members, track switches and track signals, an automatic controller device comprising means for selectively transmitting current from said source of current supply to said insulated sections, said track switches and said track signals at different time intervals in an automatic cycle, an alternating current motor operating said automatic controller device, said motor deriving its current from said source of alternating current supply and running at a speed substantially in synchronism with the frequency of said source of supply, and a toy car traveling on said track layout and characterized by an alternating current induction motor which runs at a speed bearing a substantially synchronous relation to the frequency of the source of alternating current supply, whereby a synchronous relation can be maintained between the travel of said car and the timed energization of said insulated sections, said track 30 switches and said track signals.

4. In a toy electric train system, the combination of a track layout comprising two conducting members insulated from each other and supplying current to the trains, one of said conducting members serving as a substantially continuous conductor and the other of said conducting members having insulated sections interposed therein, track switches associated with said track layout, track signals associated with said track layout, a source of alternating current supply for energizing said conducting members, track switches and track signals, an automatic controller device for controlling the distribution of current to said insulated sections, said track 45 switches and said track signals, said controller device comprising a rotatable member, an alternating current motor operating said rotatable member, said motor deriving its current from said source of alternating current supply and 50 running substantially in synchronism with the frequency of said source of supply, a group of contact devices disposed adjacent to said rotatable member and having wired connection with said insulated sections, said track switches and 55 said track signals, means moving with said rotatable member and coacting with said contact devices to cause circuits to be selectively established through said contact devices at various spaced and overlapping time intervals in an automatic cycle, and a toy locomotive travelling on said track layout, characterized by an alternating current motor which runs at a speed bearing a substantially synchronous relation to the frequency of said source of alternating current supply, whereby synchronous relation can 60 be maintained between the travel of said locomotive and the timed energization of said insulated sections, said track switches and said track signals.

5. A toy electric locomotive including an alternating current motor operatively connected to drive the locomotive, said motor comprising a stator having a rotor gap, a rotor mounted for endwise shifting movement in said gap, said 75

- rotor shifting to different positions in said gap in response to different flux densities created in said stator, and means for causing said motor to drive said toy locomotive in one direction when 5 said rotor is in one position in said gap and for causing said motor to drive said locomotive in the opposite direction when said rotor has shifted to another position in said gap.
6. A toy electric locomotive characterized by 10 an alternating current motor which runs at a speed substantially predetermined by the frequency of the alternating current supply, means for transmitting power from said motor to the drive wheels of the locomotive, said motor comprising a stator having a rotor gap, a rotor mounted for endwise shifting movement in said gap, said rotor shifting to different positions in said gap in response to different flux densities created in said stator and transmitting power to 15 said locomotive in a plurality of said different positions, and contact mechanism responsive to the shifting of said rotor for electrically controlling the operation of said locomotive.
7. In a toy electric train system, the combination of a track layout comprising a conducting member having insulated sections for conducting current to the trains, track equipment associated with said track layout, a source of current, and control means for controlling the connection of 20 said source of current with said insulated sections and with said track equipment, said control means comprising a rotatable drum, means for rotating said drum at a substantially constant speed, contact members adapted by their engagement with the conducting surface of said drum to establish circuits for said insulated sections and said track equipment, a sheet of insulating material on said drum adapted to have perforations cut therein through which said contact members are adapted to establish contact 25 with the conducting surface of said drum, said control means also comprising a manually operated keyboard including contacts adapted manually to establish circuits to said insulated sections and track equipment in shunt of said contact members and the conducting surface of said drum, whereby these circuits can be appropriately closed through said keyboard while said drum is rotating for determining the lengths 30 of the slots to be cut in said sheet of insulating material in formulating an automatic cycle in said sheet of insulating material.
8. A toy electric locomotive including an alternating current motor operatively connected to 35 drive the locomotive, said motor comprising a stator having a rotor gap, a rotor mounted for endwise shifting movement in said gap, said rotor shifting to different positions in said gap in response to different flux densities created in said stator, two separate gear mechanisms for transmitting driving power from said motor to the locomotive, and clutch means actuated by the shifting of said rotor to different positions in said gap for selecting either of said gear 40 mechanisms for the transmission of power from said motor to the locomotive.
9. A toy electric locomotive characterized by an alternating current motor which runs at a speed substantially predetermined by the frequency of 45 the alternating current supply, said motor comprising a stator having a rotor gap, a rotor mounted for endwise shifting movement in said gap, said rotor shifting to different positions in said gap in response to different flux densities created in said stator, a shaft shifting with said 50 rotor, a driving clutch element shifting with said shaft, two driven clutch elements adapted selectively to be driven from said rotor through said driving clutch element when the latter is in one or the other of its driving positions, a gear train connected between one of said driven clutch elements and the wheels of the locomotive for driving the locomotive in one direction, and a gear train connected between the other driven clutch element and the wheels of the locomotive for driving the locomotive in the other direction.
10. A toy electric locomotive including an alternating current motor operatively connected to drive the locomotive, said motor comprising a stator having a rotor gap, a rotor mounted for endwise shifting movement in said gap, said rotor shifting to different positions in said gap in response to different flux densities created in said stator, said motor comprising separate coils adapted to have the current flow therein controlled for causing the motor to rotate in one direction or the other, and contact mechanism controlled by the shifting of said rotor in said gap for controlling the current flow in said separate coils, whereby said motor is caused to drive 55 said locomotive in one direction or the other.
11. A toy electric locomotive characterized by an alternating current motor which runs at a speed substantially predetermined by the frequency of the alternating current supply, said motor comprising a stator having a rotor gap, a rotor mounted for endwise shifting movement in said gap, said rotor shifting to different positions in said gap in response to different flux densities created in said stator, shading coil means associated with said rotor gap adapted to cause said motor to revolve in one direction when the circuit of said shading coil means is closed, a second shading coil means associated with said rotor gap adapted to cause said motor to revolve 60 in the opposite direction when the circuit of said second shading coil means is closed, and contact mechanism responsive to the shifting of said rotor in said gap for selectively closing the circuits of one or the other of said shading coil means.
12. A toy electric locomotive for use in a toy electric train system of the class described, characterized by an alternating current driving motor operatively connected with the drive wheels of the locomotive and comprising a stator having a 65 rotor gap, multiple shading means on said stator to each side of said gap, and an inductive rotor constructed and so arranged with respect to said rotor gap and multiple shading means that the speed of rotation of the rotor is substantially dependent upon the frequency of the alternating current supply.
13. In a toy electric train system, the combination of a track layout comprising two conducting members insulated from each other and supplying current to the trains, one of said conducting members serving as a substantially continuous conductor and the other of said conducting members having insulated sections interposed therein, track switches associated with said track layout, track signals associated with said track layout, a source of alternating current supply for energizing said conducting members, track switches and track signals, an automatic controller device for controlling the distribution of current to said insulated sections, track switches and track signals, said controller device comprising a rotatable member, an alternating current motor operating said rotatable member, said mo- 70 75

tor deriving its current from said source of alternating current supply and running substantially in synchronism with the frequency of said source of supply, a group of contact devices disposed adjacent to said rotatable member and having wired connection with said insulated sections, track switches and track signals, means moving with said rotatable member and coacting with said contact devices to cause circuits to be selectively established through said contact devices at various spaced and overlapping time intervals in an automatic cycle and for automatically transmitting different voltages to said insulated sections at different time intervals, and a toy locomotive traveling on said track layout, character-

ized by an alternating current motor which runs at a speed bearing a substantially synchronous relation to the frequency of said source of alternating current supply, whereby synchronous relation can be maintained between the travel of said locomotive and the timed energization of said insulated sections, track switches and track signals, said motor comprising a rotor mounted for endwise shifting movement in response to different flux densities in the motor resulting from the transmission of different voltages to the locomotive, and means responsive to the shifting of said rotor for controlling the operation of the locomotive.

HARRY C. STEARNS. 15
